UNITED STATES PATENT OFFICE.

JAY J. HOGAN, OF ERIE, PENNSYLVANIA, ASSIGNOR TO HOGAN-SPENCER-WHITLEY COMPANY, OF ERIE, PENNSYLVANIA, A CORPORATION OF PENNSYLVANIA.

WASHING MACHINE.

Application filed October 15, 1923. Serial No. 668,545.

To all whom it may concern:

Be it known that I, JAY J. HOGAN, a citizen of the United States, residing at Erie, in the county of Erie and State of Pennsylvania, have invented new and useful Improvements in Washing Machines, of which the following is a specification.

Washing machines have heretofore been made of what might be termed the plunger type in which there are reciprocating elements acting as beaters upon the clothes. These devices are very efficient washers in many respects but involve an uneven load thus requiring a comparatively large motor. The continuous rotary washers with which I am familiar have faults as to massing of the clothes and also do not in some instances involve sufficient agitation for rapid washing. With the present invention I combine the rotating and plunger types of washers, utilizing the desirable function of both with some added results.

The invention is illustrated in the accompanying drawing which shows a central section of a washing machine.

1 marks the tub, 2 a stand on which the tub is mounted, 3 an electric motor mounted on the stand, 4 a drive shaft of the electric motor, 5 a gear fixed on the shaft 4, 6 a bearing for the shaft 4, the bearing being arranged in a housing 7 secured to the bottom of the tub.

The gear 5 meshes with a beveled gear 8 fixed on a vertical shaft 9. The lower end 35 of the shaft is journaled in a bearing 10 in the housing 7 and the upper end of the shaft extends through a bearing 11 secured to the bottom of the tub, the upper end of the shaft extending through the bearing.

40 A driver 12 is fixed on the upper end of the shaft by means of a pin 13. The driver is provided with a bearing 14 with an axis at an angle to the axis of the shaft 9. A shaft 15 is journaled in the bearing 14 and locked therein by a collar 16, the collar being locked to the shaft by a set screw 17.

50 A conical head 18 is locked on the shaft 15 by a pin 19. A carrier 20 has a conical hub 21 which fits on the head 18 and is clamped thereon by a thumb nut 22 screwed on to the end of the shaft 15.

55 Beaters, preferably in the form of vacuum cups 23 are mounted on the carrier and as shown are secured to the carrier by cap screws 24.

The driver is preferably housed and the clothes spaced somewhat from the center by a housing made up of the upright cylinder 25 which is secured to the bottom of the tub and a telescoping housing 26 which is carried by the driver 12. This protects the clothes from the bearings and shields the bearings from the water of the tub.

In operating the washer, the clothes are arranged around the bottom of the tub with the usual level of water and the motor is put in operation rotating the shaft 9 which rotates the driver 12. The engagement of the beaters 23 with the water and the material being washed retards the beater 60 in engagement and causes the carrier to rotate relatively to the driver. In other words, it rolls around the space above the clothes as the driver is rotated. This rotation causes the beaters to roll into the 65 water and into contact with the clothes thus depressing or beating them and as the cups are withdrawn or rolled up out of the water the pull of the cup tends to loosen and work the material. The pull incident to with- 70 drawing the cups from the water is sustained by the downward thrust of the next ingoing cup so that there is a more or less balancing of pressures. The ingoing cups are slightly inclined forwardly and the 75 driving force of these cups creates a surge which is retarded by the outgoing cup so that there is a very violent agitation both of the water and of the material due to the combined up and down, or in and out movement of the cups and the forward driving movement due to the rotation.

In order to adjust the cups to a greater or less quantity of material I prefer to adjust the height of the driver. This may be accomplished as follows: A spool 27 is fixed on the shaft 9. This spool is engaged by an arm 28 fixed on a shaft 29. A lever 30 is fixed on the shaft 29 and operates over a segment 31. The lever may be secured in 80 different positions by a pin 32 operating in perforations 33 in the segment. By moving this lever the shaft 9 may be raised or lowered, thus raising or lowering the driver and adjusting the beaters to the quantity of 85 material in the tub.

It will be noted that the cups or beaters are rigid with the carrier so that their position relative to the tub is maintained throughout the operation and there is no 90

possibility of these beaters or cups engaging or striking the walls of the tub, and that the carrier has an orbital mounting with an axis at an angle to the axis of the driver.

5 It will be noted also that the cups are in a plane of the center of oscillation. As a result the up and down movement of the cups is approximately in an arc nearly perpendicular and thus the cups operate in a 10 smaller space and more nearly in a direction to exert a beating action rather than a rubbing action. It will also be observed that this center of oscillation is within the housing, the rotating cap of the housing protecting this part from the water, or suds of the tub.

What I claim as new is:—

1. In a washing machine, the combination of a tub; a beater carrier within the tub; a 20 rotary driver; an orbital mounting for the carrier driven by the driver and having its axis at an angle to the axis of the driver; and a plurality of beaters rigidly mounted on the carrier and adapted to be depressed 25 and elevated by the orbital movement of the carrier.

2. In a washing machine, the combination of a tub; a beater carrier within the tub; a rotary driver; an orbital mounting for the 30 carrier driven by the driver and having its axis at an angle to the axis of the driver; and a plurality of cups rigidly mounted on the carrier and adapted to be depressed and elevated by the orbital movement of the carrier.

3. In a washing machine, the combination of a tub; a beater carrier within the tub; a rotary driver; an orbital mounting for the carrier driven by the driver and having its 40 axis at an angle to the axis of the driver; and a plurality of beaters rigidly mounted on the carrier and adapted to be depressed and elevated by the orbital movement of the carrier, the beaters being approximately at 45 the plane extending through the center of oscillation of said beaters.

4. In a washing machine, the combination of a tub; a beater carrier within the tub; a rotary driver; an orbital mounting for the 50 carrier driven by the driver and having its axis at an angle to the axis of the driver; and a plurality of cups rigidly mounted on the carrier and adapted to be depressed and elevated by the orbital movement of the carrier, said cups being approximately at the 55 plane extending through the center of oscillation of said cups.

5. In a washing machine, the combination of a tub; a beater carrier within the tub; a 60 rotary driver; an orbital mounting for the carrier driven by the driver and having its axis at an angle to the axis of the driver; a plurality of beaters rigidly mounted on the carrier and adapted to be depressed and elevated by the orbital movement of the car-

rier; and a housing for the mounting extending upwardly from the bottom of the tub, the mounting extending into the housing making the center of oscillation of the beaters below the top and within the housing. 70

6. In a washing machine, the combination of a tub; a beater carrier within the tub; a rotary driver; an orbital mounting for the carrier driven by the driver and having its axis at an angle to the axis of the driver; a plurality of beaters rigidly mounted on the carrier and adapted to be depressed and elevated by the orbital movement of the carrier; a housing extending upwardly from the bottom of the tub into which the mounting extends, the center of oscillation of the beaters being below the top and within the housing; and a cap for the housing carried by the mounting. 80

7. In a washing machine, the combination of a tub; a beater carrier within the tub; a rotary driver; an orbital mounting for the carrier driven by the driver and having its axis at an angle to the axis of the driver; and a plurality of beaters rigidly mounted 90 on the carrier and adapted to be depressed and elevated by the orbital movement of the carrier, said beaters being revolved relatively to the mounting by the engagement of the beaters with the work as the driver is rotated. 95

8. In a washing machine, the combination of a tub; a beater carrier within the tub; a rotary driver; an orbital mounting for the carrier driven by the driver and having its axis at an angle to the axis of the driver; and a plurality of cups rigidly mounted on the carrier and adapted to be depressed and elevated by the orbital movement of the carrier, said cups being revolved relatively to 100 the mounting by the engagement of the cups with the work as the driver is rotated.

9. In a washing machine, the combination of a tub; a beater carrier within the tub; a rotary driver; an orbital mounting for the 110 carrier driven by the driver and having its axis at an angle to the axis of the driver; a plurality of beaters mounted on the carrier and adapted to be depressed and elevated by the orbital movement of the carrier; and means for adjusting the height of the carrier. 115

10. In a washing machine, the combination of a tub; a rotary driver mounted in the tub; a beater carrier journaled on the driver with an axis at an angle to the axis of the driver; and means for adjusting the height of the carrier. 120

11. In a washing machine, the combination of a tub; a rotary driver mounted in the tub; a beater carrier journaled on the driver with an axis at an angle to the axis of the driver; and means for adjusting the driver to adjust the height of the carrier. 125

12. In a washing machine, the combina- 130

tion of a tub; a beater carrier within the tub; a rotary driver mounted in the tub and extending through and upwardly 15 from the bottom thereof; a beater carrier journaled on the upper end of the driver with an axis at an angle to the axis of the driver; and a housing for the driver comprising a cylinder extending upwardly from 20 the bottom of the tub and a cylinder extending downwardly on the driver, said cylinders being telescopically arranged.

5   a rotary driver; an orbital mounting for the carrier driven by the driver and having its axis at an angle to the axis of the driver; a plurality of beaters mounted on the carrier and adapted to be depressed and elevated by the orbital movement of the carrier; and a housing for the mounting comprising a cylinder extending upwardly 10 from the tub and a cylinder extending downwardly on the mounting, said cylinders being telescopically arranged.

13. In a washing machine, the combina-

tion of a tub; a rotary driver mounted in the tub and extending through and upwardly 15 from the bottom thereof; a beater carrier journaled on the upper end of the driver with an axis at an angle to the axis of the driver; and a housing for the driver comprising a cylinder extending upwardly from 20 the bottom of the tub and a cylinder extending downwardly on the driver, said cylinders being telescopically arranged.

In testimony whereof I have hereunto set my hand.

JAY J. HOGAN.
